US00D833031S

(12) **United States Design Patent** (10) **Patent No.:** **US D833,031 S**
(45) **Date of Patent:** **** Nov. 6, 2018**

(54) **PIPETTE TIP SHEET**

- (71) Applicant: **BIOTIX, INC.**, San Diego, CA (US)
(72) Inventors: **Scott Edward Curry**, Carlsbad, CA (US); **Arta Motadel**, San Diego, CA (US); **Peter Paul Blaszczak**, San Diego, CA (US)
(73) Assignee: **BIOTIX, Inc.**, San Diego, CA (US)
(**) Term: **15 Years**
(21) Appl. No.: **29/601,730**
(22) Filed: **Apr. 25, 2017**

Related U.S. Application Data

- (60) Division of application No. 29/527,027, filed on May 14, 2015, now Pat. No. Des. 815,753, which is a

(57) **CLAIM**

The ornamental design for a pipette tip sheet, as shown and described.

DESCRIPTION

FIG. 1 is a top perspective view of a pipette tip sheet apparatus;
FIG. 2 is an enlarged view of a portion of the sheet apparatus shown in FIG. 1;
FIG. 3 is a bottom perspective view of the sheet apparatus shown in FIG. 1;
FIG. 4 is a top view of the sheet apparatus shown in FIG. 1;
FIG. 5 is an enlarged view of a portion of the sheet apparatus shown in FIG. 4;
FIG. 6 is a bottom view of the sheet apparatus shown in FIG. 1;
FIG. 7 is a short side view of the sheet apparatus shown in FIG. 1;
FIG. 8 is an enlarged view of a portion of the sheet apparatus shown in FIG. 7; and,
FIG. 9 is a long side view of the sheet apparatus shown in FIG. 1.

1 Claim, 3 Drawing Sheets

Related U.S. Application Data

continuation of application No. 14/712,451, filed on May 14, 2015, and a continuation-in-part of application No. 14/566,143, filed on Dec. 10, 2014.
